UNITED STATES PATENT OFFICE.

CHARLES ALLEN, OF EL PASO, TEXAS.

OVERFLOW CONTROL FOR SEPARATING-TANKS.

1,296,252.

Specification of Letters Patent.

Patented Mar. 4, 1919.

Application filed August 16, 1915. Serial No. 45,821.

To all whom it may concern:

Be it known that I, CHARLES ALLEN, a citizen of the United States, residing at El Paso, in the county of El Paso and State of Texas, have invented new and useful Improvements in Overflow Controls for Separating-Tanks, of which the following is a specification.

This invention relates to an overflow control for slime thickness, settling tanks, separating tanks, and the like.

In the operation of slime thickness, separating tanks and like machines, it has been common practice to scrape the overflow edge or level it by mechanical adjustment. Such devices, in practice, have proved to be hardly more nor less than poor make-shifts, because of the exact horizontal that must be maintained where the depth of the water on the overflow lip is sometimes not greater than $\frac{1}{2}$ of an inch. Hence a deviation of $\frac{1}{2}$ of an inch from the horizontal will double the velocity of approach at one point and entirely cut off the discharge at the opposite point or side.

The object of the present invention is to provide an overflow control which will insure a uniform overflow at all points on the discharge lip of the tank under all normal working conditions, and which will not be affected by any ordinary deviation from the horizontal, due to settling, or other causes.

The invention consists of the parts and the construction and combination of parts as hereinafter more fully described and claimed, having reference to the accompanying drawings, in which—

Figure 1 is a central, vertical section of one form of overflow control.

Fig. 2 is a plan view of same.

Fig. 3 is a vertical, central section of another form of overflow control.

Fig. 4 is a plan view of same.

Fig. 5 is a plan section of one of the ten distributing compartments, showing the arrangement of holes 30, 31, 32 and 33.

Figs. 6, 7 and 8 are various modifications showing an overflow control in which the float and valve are eliminated.

The present invention has been particularly designed for use with the submerged cone of my Patents No. 942,697, dated December 7, 1909, No. 949,560, dated February 15, 1910 and No. 1,147,356, dated July 20, 1916. It will be manifest that it will be applicable wherever a nicely regulated over-

flow, or where a change in the volume or direction of overflow, may be desired.

The receptacle to which the device may be attached may or may not have a discharge for solids, or a portion of the water, at the bottom, or anywhere below the overflow line. The water or solution to be handled may be fed at the center or one side of or in any other desired way into the tank; the method of feeding being immaterial.

In carrying out my invention, A indicates the main settling tank and 2 the discharge launder. Suitably secured, with relation to the upper end of the tank, and concentrically positioned within same, is a ring 3 which is sufficiently deep to extend above the water level shown and below the discharge lip 4 of tank A. Formed in the discharge launder is a float receptacle 5, in the bottom of which is mounted a discharge valve 6 which is opened and closed automatically by means of a float 7. This is provided for the purpose of maintaining a water level which normally extends above the discharge lip 4 of tank A.

In operation, the pulp is delivered to the center of the tank by means of a pipe or launder 8. The solids contained in the water will settle through the ring 3 and collect in the bottom of the tank A, from where they may be discharged in any suitable manner (not here shown). Any solids or liquids that have a tendency to float will rise to the surface within the circular band 3 and will be prevented from floating into the launder 2. The water entering with the pulp flows under the lower edge of the band 3, then upward in the direction of the arrows and over the discharge lip of tank A into launder 2, and thence into the float receptacle 5 and out through the spigot or valve 6 which is controlled by the float 7. The normal water level is thus maintained in the tank and launder because as the water level rises, it raises the float, thereby opening the valve in proportion to its rise. The normal water level is above the overflow edge 4, and the lower edge of ring 3 below the level of the discharge lip 4. Under these conditions, should the tank A settle on one side, or in any manner deviate from a true horizontal, it is without effect on the flow of water from the center to the periphery until a point is reached when some portion of the discharge lip or edge 4 projects above the surface of

- the normal water level. Hence any reasonable uneven settling does not affect the uniformity of the flow over the periphery or discharge lip of the tank. This insures uniform results in the settling or clearing of the water within the tank without releveling the tank or trimming the overflow edge as has heretofore been necessary in settling tanks commonly in use.
- When employing the overflow control shown in Figs. 1 and 2, it has been found that it is practically impossible to maintain a uniform flow from the center to all parts of the periphery of the tank, as the greatest volume of the overflow will take a more or less direct line from the point of its entrance to the discharge through the float receptacle and discharge valve 6.
- For the purpose of overcoming such tendency and insuring a uniform flow from the center to all points of the overflow periphery, the following means have been provided: Referring to Figs. 3 and 4, it will be seen that the discharge launder has been divided into five annular spaces, such as indicated at 9, 10, 11, 12 and 13, by means of vertically disposed ring-shaped partition plates 14, 15, 16, 17 and 18. These annular spaces are in turn divided by radially disposed partition plates, such as indicated at 19, 20, 21, 22, 23, 24, 25, 26, 27 and 28, into ten sections, and the overflow into each of these sections is discharged through a separate pipe, indicated at 29, into the float receptacle 5. Each of these pipes controls $\frac{1}{10}$ of the overflow periphery 4; each pipe has the same velocity head to its flow; and hence each discharges the same volume. If these ten pipes were directly connected to the upper part of the tank, there would be ten points where the flow from the center to the periphery would be concentrated, whereas, it is desirable to have a uniform flow at all points. This is obtained by the use of a series of holes in the circular rings 14, 15, 16, 17 and 18, and as all the ten sections, into which the launder 2 is divided, are exactly alike, the same description will refer to all.
- The water overflowing in all the ten sections passes through sixteen equidistant holes, such as indicated at 30, into the space 10, then through eight equidistant holes 31 into the space 11, thence through four equidistant holes 32 into the space 12, thence through two holes 33 into the space 13 from where the total volume is permitted to discharge through the connected pipe 29 into the float receptacle. As there is the same velocity head to the flow through every one of the holes in the inner partition and the same friction and distance of travel to the flow from every one of the inner holes to its final discharge, there will be a uniform velocity of flow from the center to all points of the overflow periphery. In the present instance

there are one hundred sixty holes on the inside partition ring 15. This number may be increased or decreased as may be found best to accomplish the desired result.

From the foregoing description, it will be seen that settling of the tank under normal conditions to one side or the other will not in any way effect a uniform discharge at all parts of the periphery of the tank unless settlement should take place to such an extent as to raise one side of the upper overflow end of the tank above the normal water level. This would, however, seldom take place and can easily be remedied by trimming the tank, if such extreme settlement of the supporting frame or base should take place.

The provision of the float 7, with connected valve 6, automatically maintains the desired water level and this may be raised or lowered by adjusting the length of the connecting rod between the float and valve. The uniform flow to all points to the discharge periphery is, furthermore, obtained by the novel arrangement of the ten compartments and the plurality of escape openings formed therein.

By referring to Fig. 7, it will be seen that a constant water level above the discharge lip of the tank may be maintained without the use of the float and connected valve heretofore described. This is accomplished by providing an overflow lip, such as indicated at 40; this form of discharge being used when practically no solids have a tendency to discharge with the overflow.

In Fig. 8 the siphon discharge 41 has been provided. This is used where solid particles brought to the outer section of the launder have a tendency to accumulate. The velocity produced by the siphon discharge causes a complete removal of same.

In Fig. 6, which is a detail view of one side of the overflow, the holes or perforations between the several compartments are shown as arranged on an angle. This is for the purpose of carrying off solids that have a tendency to escape with the overflow. If solids accumulate in the outer compartment to any extent, the outer hole is connected with a siphon pipe, such as indicated at 43, while where there is practically an absence of solids in the overflow the ordinary discharge lip shown in Fig. 7 may be employed.

From the description of Figs. 6, 7 and 8, it will be seen that a constant water level may be maintained above the discharge lip of the tank without the use of the float and valve previously described. This not only simplifies the construction in general but also makes it easier and cheaper to manufacture and operate.

The materials and finish of the several parts of the device are such as the experience and judgment of the manufacturer may dictate.

I wish it understood that various changes in form, proportions and minor details of construction may be resorted to within the scope of the appended claims and that I do not wish to limit myself to the specific design and construction here shown.

Having thus described my invention, what I claim and desire to secure by Letters Patent is—

- 10 1. In a device of the character described, the combination with the settling tank, of a discharge launder exteriorly of the tank and surrounding same, and automatic means for maintaining a constant water level in the 70
15 launder higher than the upper overflow end of the tank, said means comprising a float actuated valve mounted in the discharge launder and regulating the discharge therefrom.
- 20 2. In a device of the character described, the combination with the settling tank, of a discharge launder exteriorly of the tank and surrounding the same, a float actuated valve in the launder for maintaining a constant water level therein higher than the 80
25 upper overflow end of the tank, and means for producing a uniform discharge at all points on the periphery of the tank into the launder.
- 30 3. In a device of the character described, the combination with the settling tank, of a discharge launder exteriorly of the tank and surrounding same, means for maintaining a normal water level in the launder which will keep the upper overflow end of the 85
35 tank submerged, and a circular band secured concentrically with relation to the tank, having its upper edge extending above the water level and its lower edge below the
40 upper overflow end of the tank.
4. In a device of the character described, the combination with the settling tank, of a discharge launder exteriorly of the tank and surrounding same, a float chamber in 90
45 the launder, a discharge valve in the bottom of the chamber, and a float connected with the valve to open and close same to maintain a normal water level in the launder which will keep the upper overflow end of the tank submerged.
5. In a device of the character described, the combination with the settling tank, of a discharge launder exteriorly of the tank and surrounding same, a float chamber in 95
55 the launder, a discharge valve in the bottom of the chamber, a float connected with the valve to open and close same to maintain a normal water level in the launder which will keep the upper overflow end of the tank submerged, and a circular band secured concentrically with relation to the tank having its upper edge extending above the water level and its lower edge below the upper overflow end of the tank.
6. In a device of the character described, the combination with the settling tank, of a discharge launder exteriorly of the tank and surrounding same, a float chamber in 100
60 the launder, a discharge valve in the bottom of the chamber, a float connected with the valve to open and close same to maintain a normal water level in the launder which will keep the upper overflow end of the tank submerged, and means for producing a uniform discharge at all points on the periphery of the tank into the launder.
7. In a device of the character described, the combination with the settling tank, of a discharge launder exteriorly of the tank and surrounding same, a plurality of radially disposed plates in the launder to divide the launder into a plurality of compartments, a plurality of plates in each compartment dividing each compartment into a plurality of separated chambers, said plates having a plurality of perforations formed therein to form communication between each chamber, a float chamber, a discharge valve in said chamber, a float in the chamber connected with the valve to open or close same to maintain a normal water level in the several compartments and chambers in the launder which will keep the discharge lip of the tank submerged, and a pipe connecting each compartment with the float chamber. 95
80
85
8. In a slimer, the combination with the settling tank, of a launder exteriorly of the tank and surrounding the same, and means for producing a uniform flow from the center of the tank to all points of the 100
105 discharge lip, said means comprising a series of annular ring members, positioned one exteriorly of the other within the launder and interspaced, a plurality of openings formed in the innermost of said rings, and a decreasing number of openings formed in the succeeding rings.
9. In a slimer, the combination with the settling tank, of a launder exteriorly of the tank and surrounding the same, and means for producing a uniform flow from the center of the tank to all points of the discharge lip, said means comprising a series of annular ring members, positioned one exteriorly of the other within the launder and interspaced, a plurality of openings formed in the innermost of said rings, a decreasing number of openings formed in the succeeding rings, and radially disposed partition plates interposed between the ring members 110
115 to form a plurality of separate compartments for the flow of the pulp.
10. In a device of the character described, the combination with a settling tank having an overflow periphery, of means to supply 120
125 pulp to said tank, a discharge launder adapted to receive the overflow, means in said launder for maintaining a water level in the launder higher than the overflow periphery of the tank, and means in the 130

launder for maintaining an even flow from the center of the tank to all points on the overflow periphery, said means comprising a plurality of perforated distributing rings positioned in the launder.

5 In testimony whereof I have hereunto set

my hand in the presence of two subscribing witnesses.

CHARLES ALLEN.
